UNITED STATES PATENT OFFICE.

HEINRICH RENCK, OF HAMBURG, GERMANY.

PROCESS FOR THE PRODUCTION OF PRINTING PLATES.

No Drawing.

Application filed April 25, 1922. Serial No. 556,418.

To all whom it may concern:

Be it known that I, HEINRICH RENCK, a citizen of the German Republic, and resident of No. 11 Elsastrasse, Hamburg, Germany,

5 have invented certain new and useful Improvements in Processes for the Production of Printing Plates, of which the following is a specification.

It has already been suggested, for the 10 manufacture of printing plates, when bichromated gelatine plates are used, to develop the plates after their exposure to light in cold water and then to subject them to the action of dry heat.

15 It is further known, when using silver halid gelatine plates, to harden the same with formalin after their exposure to light and development with pyrogallol and then to dry same quickly with the application of 20 higher temperatures.

In contradistinction thereto according to this invention, the improved process consists in subjecting the bichromated gelatine plates after their exposure to light to the 25 action of moist steam. The steam treatment takes place immediately—in the case of bichromated gelatine plates—after their exposure to light, with the result that plates ready for printing are at once obtained. If

silver halid gelatine plates, or the like, are 30 used, prehardening must be effected after their exposure to light and development before the steam treatment is carried out.

The steam treatment is carried out in such a manner that the prepared gelatine 35 plates are exposed to steam of a temperature which will be below the melting point of the non-exposed gelatine.

The advantages of the process according to this invention are that it is simpler and 40 requires less time to carry out than the known processes. Furthermore dry plates ready for immediate printing are obtained thereby.

I claim—

1. The method of making gelatine print- 45 ing plates, which comprises exposing a sensitized gelatine plate, and developing the plate with moist steam.

2. The method of making gelatine print- 50 ing plates, which comprises exposing a bichromated gelatine plate and developing the same with moist steam of a temperature below the melting point of the non-exposed gelatine portion of the plate.

Signed by me at Hamburg, this 27th day 55 of March, 1922.

HEINRICH RENCK. [L.s.]
